UNITED STATES PATENT OFFICE.

RALPH H. NORTH, OF PHILADELPHIA, PENNSYLVANIA, ASSIGNOR TO THE
NORTH BROTHERS MANUFACTURING COMPANY, OF SAME PLACE.

FASTENER FOR MEETING-RAILS OF SASHES.

SPECIFICATION forming part of Letters Patent No. 391,813, dated October 30, 1888.

Application filed August 24, 1888. Serial No. 283,665. (No model.)

To all whom it may concern:

Be it known that I, RALPH H. NORTH, a citizen of the United States, residing in the city and county of Philadelphia, and State of Pennsylvania, have invented certain new and useful Improvements in Sash-Holders, of which the following is a specification.

The present invention relates to that class of sash holders or locks in which a movable member is held in an open socket. It, however, relates more particularly to the class of sash holders or locks set forth and shown in United States Letters Patent No. 379,242, granted to me March 13, 1888.

15 The invention consists in providing a sash-holder that is composed of separable members with a detachable confining-plate, whereby when the members are assembled and not connected with a sash the plate will hold them together and prevent them from becoming disassociated, the construction being such that the plate is detachably secured in place and prevented from accidental dislodgment.

25 The accompanying drawings illustrate the improvement in connection with a sash-holder substantially like that shown in my said patent, in which drawings—

30 Figure 1 is a perspective view looking at the under side of a case containing a movable bolt or catch and provided with the improved confining-plate. Fig. 2 is a sectional elevation of the same, taken on the line 22 of Fig. 1, shown in position and secured to a sash. Fig. 3 is a plan view of the under side of the case, 35 the movable bolt or catch and confining-plate being removed. Fig. 4 is a perspective view of the confining-plate.

Prior to my invention it had been found desirable to form the case for the movable bolt 40 with an open socket for containing the bolt, so as to obviate the necessity for using a core in the casting operation to form an inclosed socket therefor, and in order to prevent the movable bolt from wearing away the sash it 45 became necessary to supplement the case with a plate adapted to be contained in a recess in the under side of the case and below the bolt, which plate was a loose one and only held to its place when the case was secured to the sash. 50 In such a construction it is obvious that said

loose plate had no effect to hold the parts of the lock together when not secured to the sash, and when the case was handled it necessitated also handling the plate, and when it was to be secured to the sash it required that the plate 55 be carefully inserted in place in its recess in the case and kept so until the case was properly secured.

In order to obviate these disadvantages and to increase the efficiency of this class of devices, 60 the improvement consists, essentially, in providing the underside of the case with a seat for a detachable plate and a plate adapted to said seat and held therein against accidental displacement, whereby when the parts were assembled they would remain so until it was desired to disassociate them by removing the plate.

The sash-lock taken for illustration consists, as in my said patent, of the bolt section or case 70 A, having an open socket, d, from which socket extends horizontal flanges e, providing means for securing the section or case to the rail of a sash, B. Within the socket d is seated the cylindrical bolt C, having a locking-finger at 75 its outer end and provided with an operating-handle, b, which extends through a cam-slot, e, in said socket of the section or case. With this section of course will be used a keeper 80 adapted for attachment to the meeting-rail of 80 the other sash, and with which keeper the end of the bolt C engages as it is turned for that purpose, and by which the two sashes are secured. As this portion of the sash holder or lock forms no part of the present invention, no 85 illustration of the same is given. One form of keeper is fully shown and set forth in my said patent.

The under side of the case A, and upon opposite sides of the depression formed by the socket 90 d, is formed with a depressed seat, 10, extending substantially the width of the case, as shown, and providing shoulders 12 upon the opposite sides of the seat to better confine the plate D in place. These shoulders may be undercut 95 to provide overlapping tongues to engage with the plate and hold it in place in the seat. In practice, however, I prefer to provide one or more tongues, 13, upon opposite sides of the depressed seat 10, the inner edge of which ex- 100

tends slightly beyond the line of the shoulder 12 upon the same side of the seat, which tongues are undercut, as shown at 9, Fig. 2, so as to permit the edges of the plate D when moved into 5 proper position in the seat to extend between said tongues and the seat, thus holding the plate in place. The opposite edges of the plate D may be inclined, as shown, to better adapt it to slide between the tongues and the 10 seat and be properly held by said tongues. The tongues 13 may also extend slightly beyond the surface or under side of the case A, as shown in Fig. 2, and thus strengthen them considerably. While these tongues may be 15 placed at any point along the sides of the depressed seat, they are preferably located at the points at which the cam-slot c, formed in the socket d, meets the horizontal flanges e of the case, and, as shown, extend from said flanges 20 inwardly over the opening formed by said cam-slot. This greatly simplifies the construction of the case and tongues and renders their manufacture as easy as in cases without the tongues, the position of the tongues and their uncut sides 25 being suited to the "draft" in the casting operation.

The plate D may be more effectively held in place by the tongues 13 by forming it slightly tapering in width, so that when it is slid onto 30 its seat from the open end thereof the plate may be pushed hard enough under the tongues to become wedged sufficiently therebetween to withstand ordinary handling and prevented from becoming loose. The seat 10 of course 35 may also be slightly tapered to correspond with the taper of the plate D.

What I claim is—

1. The herein-described case for sash-holders, provided upon its under side with a seat having oppositely-projecting tongues and a detachable plate adapted to said seat and to be 40 removably held in place by said tongues.

2. The herein-described case for sash-holders, provided upon its under side with a seat having oppositely-projecting and undercut 45 tongues and a detachable plate having inclined or beveled sides adapted to said seat and to be removably held in place by said tongues.

3. The herein-described case for sash-holders, provided upon its under side with a seat 50 having oppositely-projecting tongues and a detachable plate tapering in width, adapted to slide on the seat under the tongues and be wedged between the tongues and the seat.

4. The herein-described case for sash-holders, having an open socket, a revolving bolt contained thereby, and a cam-slot for projecting the bolt, the said case provided with oppositely-projecting tongues extending over the opening formed by the cam slot and a removable 55 plate adapted to be confined to the case by said tongues.

In testimony whereof I have signed my name to this specification in the presence of two subscribing witnesses.

RALPH H. NORTH.
